UNITED STATES PATENT OFFICE.

AXEL JOHNSON, OF OAKLAND, CALIFORNIA, ASSIGNOR TO AMERICAN CAN COMPANY, OF SAN FRANCISCO, CALIFORNIA, A CORPORATION OF NEW JERSEY.

DOUBLE-SEAMER.

1,349,837.

Specification of Letters Patent. Patented Aug. 17, 1920.

Application filed March 24, 1917. Serial No. 157,258.

To all whom it may concern:

Be it known that I, AXEL JOHNSON, a citizen of the United States, residing at Oakland, in the county of Alameda and State of California, have invented certain new and useful Improvements in Double-Seamers, of which the following is a specification.

The present invention relates to a machine for seaming ends to flanged can bodies, as, for example, cans used for the preservation of food products and other similar materials.

In machines of this type it is usual practice to seam the adjacent flanges of the can body and the end in two operations, for the reason that a suitable seam cannot be formed properly in one operation. The machines for this purpose have heretofore usually employed two rotating rolls for forming the seam, one roll for each operation, and various means have been used for bringing the two rolls into operative relation with the flange of the can to form the seam. Obviously, means must be provided for adjusting the rolls relatively to the can to be seamed, and in machines employing two rolls for the production of a seam, each roll requires an adjustment of its own. Inasmuch as a very slight error in the adjusting of the rolls will result in an imperfect or leaky seam, it is highly desirable to reduce the chance for the occurrence of this error to a minimum. This is done in the present invention by using one roll for both seaming operations, said roll being provided with two adjacent grooves in its periphery, each groove adapted for performing one operation. In this case the roll need be adjusted but once for both operations, inasmuch as the relative positions of the two seaming grooves formed therein do not change.

A further object of the invention is to provide a machine which handles the cans continuously, thereby avoiding the stopping and starting of its working parts and saving it from the strains and wear incident to intermittent operation. And a further object is to prevent a very disagreeable feature connected with machines having intermittent operation. Where these machines are used in canning factories for closing filled cans, there is a great loss of contents due to the starting and stopping of filled cans. The contents of the cans being more or less in a

liquid condition, the sudden starting and stopping causes more or less spilling, which soils the cans and machine, and during a day's run produces a very unsanitary and messy looking condition. All cans do not spill uniformly, with the result that the uniform work of the filling machines is more or less negatived through the unavoidable spilling by an intermittently moving closing machine. In the present type of machine, however, where the cans move continuously in processional arrangement, and have their covers securely clamped on and double seamed thereto while they are continuing their forward movement, practically all loss from spillage is avoided. The cans and machines remain cleaner in operation, and a generally better and more satisfactory product is produced.

In order to comprehend the invention, reference should be had to the accompanying sheets of drawings, wherein—

Figure 1 is a plan view of the machine, showing the entrance belt, the feeding disk and the main casing of the machine, the driving connection to the spindles being shown in dotted lines within the casing.

Fig. 2 is a longitudinal sectional view taken on the broken lines 2—2 of Fig. 1, of the drawings viewed in the direction of the arrows, excepting that the entire disk 28 is shown in section, and showing the arrangement of the seaming devices and the driving mechanism of the various working parts of the machine.

Fig. 3 is a broken horizontal section taken in the direction of the arrows on the broken line 3—3 of Fig. 2 of the drawings, showing the chuck control mechanism.

Fig. 4 is a broken horizontal section taken in the direction of the arrows on the broken line 4—4 of Fig. 2 of the drawings, showing the seaming roll mechanism.

Fig. 5 is a sectional plan view taken on the line 5—5 of Fig. 2 of the drawings, showing the path of travel of the cans through the machine, and the chucks and seaming rolls.

Fig. 6 is a fragmental detail view, enlarged, of one of the seaming mechanisms, taken approximately on the broken line 6—6 of Fig. 4 of the drawings, and viewed in the direction of the arrows.

Fig. 7, is a fragmental detail view, enlarged, of a seaming roll and a portion of

the seaming chuck, showing a can and end in place beneath the chuck and illustrating the first seaming operation being performed upon the flanges of the can and end.

5 Fig. 8 is a view similar to Fig. 7, illustrating the second seaming operation upon the flanges of the can and end.

In the drawings, and referring particularly to Fig. 2 thereof, the reference numeral 1 designates a suitably constructed base, preferably tubular in form. This base is provided at its upper end with an annular grooved flange 2 within which rests a horizontally disposed rotatable turret plate 3. Said turret plate is permanently connected to, or as is here shown, formed integral with a hub 4, the lower end of which extends into the base 1 and carries therein an annular gear ring 5. Said gear ring 20 meshes with and is adapted to be driven by a smaller gear 6 fixed upon the upper end of a short vertical shaft 7 journaled in one side of the base 1, and carrying upon its lower end a bevel gear 8. A similar bevel gear 9, adapted to mesh with said gear 8, is carried upon a horizontally disposed drive shaft 10, journaled in the base at 11 and carrying upon its outer end a pulley 12 for receiving power from an outside source, not shown in the drawings.

The base 1 supports an upwardly extending vertical column 13, Fig. 2 of the drawings, upon which the hub 4 of the turret is journaled, as at 14, and which supports, by means of internal journals 15, a vertical shaft 16, said shaft having at its lower end a bevel gear 17 adapted to mesh with and be driven by a similar gear 18 mounted upon the drive shaft 10. It will be seen from Fig. 2 of the drawings, that the turret 3 is rotated slowly by means of the gears 5 and 6 and 8 and 9, and that the central shaft 16 is rotated more rapidly by means of its gears 17 and 18.

45 The hub 4 of the turret carries at its upper end a head 19, over which is the housing 20. Said head and housing inclose the various devices for operating the can chucks and the seaming rolls in a manner to be hereinafter described.

A feed table 21—Figs. 1, 2 and 5 of the drawings, extends laterally and horizontally from the base 1 and is flush with the surface of the horizontal turret table 3. A conveyer, here shown as comprising a belt 22, running over a pulley 23, is provided for bringing cans onto said feed table. The cans, which are designated by the numeral 24, are understood to have ends 25 applied thereto in preparation for seaming. Said cans are guided, as brought in by the conveyer belt 22, by guide rails 26 and 27—Figs. 1 and 5 of the drawings. A can feed wheel 28, Figs. 1, 2 and 5, is mounted horizontally above the feed table 21, upon a

vertical shaft 29. Said shaft carries at its lower end a bevel-gear 30—Fig. 2, adapted to mesh with a bevel-gear 31 mounted upon the end of the drive shaft 10.

The can feed wheel 28 is formed with a plurality of peripheral pockets 32, Figs. 1, 2 and 5 of the drawings, adapted successively to engage and advance the cans 24 as the same are brought into the sphere thereof by the feed belt 22. Said feed wheel acts as a timer to place the advancing cans in timed and spaced relation, the circular portions 33 of said wheel serving as a guard for holding the can back as shown in Fig. 5 until the next following pocket 32 engages and advances said can, as shown in Fig. 1, of the drawings. The cans are advanced successively by the pockets 32 of the feed wheel 28 and are guided in their path of travel by a curved extension 34 of the guide-rail 27. Said extension is backed by a spring 35, Figs. 1 and 5 of the drawings, so that in case a can becomes misplaced with respect to the pocket 32 of the feed wheel, it will not be crushed between said wheel 90 and the guide rail 34.

The horizontal table 3 of the turret carries a plurality of freely rotatable can rests 36, Fig. 2 of the drawings. The cans as advanced in timed relation by the feed wheel 28 are deposited upon said rotatable rests. Fixed brackets 37 are provided behind said can rests 36 to insure the proper positioning of the cans thereupon. The head 19 of the turret carries, in vertical alignment with each can rest, a chuck spindle 38, rotatable in said head and carrying upon its lower end a chuck 39 adapted to engage the end 25 of the can 24 supported by its associated rotatable rest 36. The upper end of said spindle 38 is hollow and is adapted to receive a shaft 40 which extends upwardly and is secured within the hub 41 of the gear 42, said gear having a bearing for its hub at 43 in the upper portion of the housing 20, and meshing with a larger gear 44 carried upon the upper end of the central shaft 16. The spindle 38 is adapted for axial sliding movement within its bearing in the head 19 and for similar movement with respect to the shaft 40, a key 45 being provided to transmit rotation from said shaft to said spindle. Thus it will be seen that the spindles are rotated at a comparatively high speed by means of the central shaft 16 and the gears 44 and 42.

The upper end of the chuck spindle 38 carries a trunnion 46, Figs. 2 and 3 of the drawings. A forked lever 47 is fulcrumed upon a bracket 48 fixed to the turret head and has its forked ends connected with the trunnion 46. The other end of said lever carries a cam follower 49 adapted to lie within and follow an offset cam groove 50 formed in the peripheral surface of a stationary cam mem-

ber 51, secured to the upper portion of the column 13. Thus as the turret revolves about said column, the chuck carrying spindles 38 are lowered and raised by the 5 action of the cam groove 50, to cause the chucks 39 to engage and release the can ends 25 at the proper times.

The turret head 19 carries a seaming head 52, Figs. 2, 5 and 6 of the drawings, adjacent to each can end chuck 39. Said seaming head is mounted upon the lower end of a spindle 53 which is journaled for oscillatory and lineal movement at 54, Fig. 6 of the drawings, in the head 19, and which 15 carries upon its upper end a transverse double arm 55, Figs. 4 and 6 of the drawings. Said arm 55 carries upon its ends cam following rollers 56 and 57, the former below and the latter above said arm, and 20 adapted to follow cams 58 and 59 respectively, formed upon the peripheral surface of the stationary cam member 51. The function of said cam is to oscillate the seaming head 52 to bring the seaming roll 60, carried thereby into operative relation with the 25 cam seam in a manner to be presently described.

The seaming head spindle 53 also carries a cam following roller 61, Figs. 2, 4 and 6, 30 which is adapted to lie within and follow an offset groove 62 formed in the stationary cam member 51 below the groove 50 and between the peripheral cams 58 and 59. Said cam groove 62 operates to raise and 35 lower the seaming head, as will be presently described.

The seaming head 52 is in the form of a lever extending from the spindle 53, as shown in Figs. 5 and 6 of the drawings, and 40 carries in its end the seaming roll 60, the latter being freely rotatable upon a pin 63 Fig. 5 of the drawings. Said seaming roll is formed with two adjacent peripheral grooves 66 and 67, Figs. 6, 7, and 8 of the 45 drawings, the lower groove 66 performing the first operation upon the can seam, as illustrated in Fig. 7, and the upper groove 67 performing the final operation thereon, as in Fig. 8 of the drawings.

50 In the seaming operation, the seaming head 52 is first oscillated by the cams 58 and 59 to bring the lower seaming groove 66 of the roll 60 into engagement with the seam of the rotating can for initially curling the 55 same. The roll is then drawn radially with reference to the can chuck out of engagement with said seam and is lowered by means of the cam groove 62 to bring the second seaming groove 67 into alignment 60 with said seam, and the head is then again oscillated to bring said roll into engagement with said seam for the final operation thereupon.

In the operating of the machine, the can 65 24 with the ends 25 resting thereupon are

brought into the sphere of action of the feed wheel 28 by the conveyer belt 22 without regard to time or space, and are picked up by the pockets 32 of said feed wheel and advanced thereby in the proper timed and 70 spaced relation for positioning successively upon the rotatable can rests 36 of the turret plate 3. Immediately after the positioning of a can 24 upon a can rest 36, the chuck 39 is brought downward by means of 75 the cam groove 50 to clamp the can end 25 and the can 24 upon said rest. The can chuck, it is understood, rotates continuously so that when the can is engaged thereby, said can is also caused to rotate. The seam is 80 then formed in the manner previously described, that is, first by the action of the lower groove 66 of the roll 60 and finally by the action of the upper groove 67 of said roll, the seaming head 52 being oscillated 85 and moved downwardly for this purpose, as described. After the completion of the seam, the seaming roll is moved out of engagement therewith, and returned to its former upper position in readiness to cause 90 the lower seaming groove 66 to engage the seam of the next can placed within the sphere thereof.

It is understood that the turret and its head are preferably rotated continuously, 95 the cams being placed thereon at the position A, Fig. 5 of the drawings, and removed therefrom, at the position B, by means of a guide rail 68, to any suitable place of deposit, not shown in the drawings. In the machine herewith illustrated, I have shown four sets of seaming mechanism carried by the turret, each having a seaming head, a chuck and a can rest. It is to be understood, however, that the number of said sets of mechanism is not to be limited to four, but that any number thereof, consistent with structural practicability, may be employed.

100 It will be seen from the foregoing description that but one adjustment need be provided for the seaming roll, the means for providing said adjustment forming no part of the present invention, and being therefore not illustrated. On account of 115 the constant relation between the first and second seaming grooves the seaming or hermetic sealing will be perfectly formed by the one seaming roll when properly adjusted.

I do not wish to be construed as limiting my invention to the preferred form of apparatus herein described and herewith illustrated, for the reason that changes in the form and construction of the working 125 parts may be made therein, without departing from the spirit of the invention. On the contrary, it is my wish to be understood as claiming the invention as broadly as the state of the art will permit.

I do not claim herein combinations comprising seaming rolls constructed with single seaming grooves, the same being the subject of my application Serial No. 5 108,594, filed July 11, 1916.

Having thus described my invention, what I claim as new and desire to protect by Letters Patent is:

1. In an apparatus for the described purpose, the combination of a rotating member provided with a plurality of can seats, means for successively delivering cans with loosely applied covers to said seats, devices associated with each seat for clamping the said can and cover together, a seaming roll located adjacent each of said can seats, each of said rolls being provided with a plurality of seaming grooves, and means for successively bringing the grooves 10 of each roll and a can into operative relation whereby the can and end are united by a double seam.

2. In an apparatus for the described purpose, the combination of means for successively moving cans, having covers loosely applied, in processional arrangement, a plurality of seaming rolls arranged in spaced relation along the path of said cans, each of said rolls having a 20 plurality of seaming grooves, and automatic means connected with said can-moving means and coöperating for producing the movements of the rolls, for bringing the said cans and the grooves of said rolls successively into operative relation whereby the loosely applied covers are securely 30 united to said cans by a double seam.

3. In an apparatus for the described purpose, the combination of means for successively moving cans, having loosely applied covers, continuously in processional arrangement, a plurality of seaming rolls arranged in spaced relation along the path traversed by said cans, each of said rolls having a plurality of seaming grooves, and automatic means connected with said can-moving means and coöperating for producing the movements of the rolls, for bringing the grooves of said rolls successively into 40 operative relation with advancing cans, whereby the loosely applied covers are securely united to said cans by a double seam.

4. An apparatus for the described purpose, comprising the combination of means for continuously moving cans having loosely applied covers in processional arrangement, a plurality of seaming rolls arranged along the path traversed by said cans, each of said rolls having a plurality 50 of seaming grooves, and means for successively bringing the grooves of each roll into operative relation with a continuously moving can whereby the loosely applied covers are securely united to said cans by an interlocking seam.

5. An apparatus for the described purpose, comprising the combination of means for continuously moving cans having loosely applied covers in processional arrangement, a plurality of seaming rolls arranged along the path traversed by said cans, each of said rolls having a plurality of seaming grooves, and means for successively bringing the grooves of each roll into operative relation with a continuously moving can whereby the loosely applied covers are securely united to said cans by an interlocking seam, together with means for securely holding said cans and covers while in operative relation with said rolls. 70

6. In an apparatus for the described purpose, a rotatable turret, devices carried thereby for holding a flanged can and an end to be seamed thereto, mechanism for rotating said holding devices and said can and end, a seaming roll having formed therein a plurality of seaming grooves, and mechanism carried by said turret and actuated by the rotation thereof for moving said seaming roll to bring the grooves thereof successively into engagement with the flange of said can for the seaming of the end thereto. 75

7. In an apparatus for the described purpose, a continuously rotating turret, devices carried thereby for holding a flanged can and an end to be seamed thereto, mechanism for continuously rotating said holding devices and said can end, a seaming roll carried by said head, said roll having formed therein a plurality of seaming grooves, and mechanism carried by said turret and actuated by the rotation thereof for moving said seaming head radially and axially with respect to said can to bring 90 said seaming grooves successively into engagement with the flange of said can for the seaming of the end thereof. 95

8. In a machine for the described purpose, a rotatable turret, a freely rotatable can rest carried thereby and adapted to hold a flanged can having an end resting thereupon, a vertically movable and rotatable chuck adapted to engage said can end, mechanism for rotating said chuck, devices carried by said turret and actuated by the rotation thereof for moving said chuck into and out of engagement with said can end, a seaming head carried by said turret adjacent to the flange of said can, a seaming roll carried by said head, said roll having formed in its periphery a plurality of seaming grooves, and mechanism carried by said turret and actuated by the rotation thereof for moving said seaming head axially and radially with respect to said can for bringing the seaming grooves of said roll into engagement successively with the flange of said can for the seaming of the end thereto. 110 115

9. In an apparatus for the described pur- 120 125

pose, the combination with a horizontally rotating member provided with a plurality of rotating can seats, means for delivering successively to said seats flanged cans with 5 ends loosely applied thereto, devices associated with each seat for holding the can and end clamped thereto, an axially and radially movable seaming roll provided with a plurality of peripheral seaming grooves and 10 means for moving said seaming roll to place the seaming grooves thereof into engagement successively with the flange of the held can for the double seaming of the end thereto.

15 10. In a can closing machine having

means for advancing the cans and covers continuously, the combination therewith of double grooved seaming rolls which are movable vertically and horizontally, and in engagement with covered cans on said advancing means, and means connected with said advancing means for moving said rolls vertically and horizontally to perform two 20 seaming operations.

In testimony whereof I have signed my 25 name to this specification in the presence of a subscribing witness.

AXEL JOHNSON.

Witness:

N. A. ACKER.
